(57) **CLAIM**

I claim the ornamental design for a sink organizer, as shown and described.

DESCRIPTION

FIG. 1 is a perspective drawing of the invention, illustrating a plurality of dispensers of the present design and dispenser pumps in phantom outline, the dispenser pumps not constituting a part of the present design.

FIG. 2 is a front elevational view of the invention.

FIG. 3 is a rear elevational view of the invention, illustrating a towel rack and a sponge holder of the present design.

FIG. 4 is a left-side elevational view of the invention.

FIG. 5 is a right-side elevational view of the invention.

FIG. 6 is a bottom plan view of the invention, illustrating apertures in a bottom portion of the sponge holder.

FIG. 7 is a top plan view of the invention.

FIG. 8 is a cross-sectional view of the invention, taken generally along lines 8—8 of FIG. 3; and,

FIG. 9 is a cross-sectional view of the invention, taken generally along lines 9—9 of FIG. 2.
